UNITED STATES PATENT OFFICE

139,429

DESIGN FOR A WALLET

Charles Meyers, New York, N. Y.

Substituted for abandoned application Serial No.
112,382, January 31, 1944. This application
October 5, 1944, Serial No. 115,638

Term of patent 14 years

(Cl. D87—3)

To all whom it may concern:

Be it known that I, Charles Meyers, a citizen of the United States of America, and a resident of the county of Bronx, city and State of New York, have invented a new, original, and ornamental Design for a Wallet, of which the following is a specification, reference being had to the accompanying drawing, forming a part thereof.

This application is a substitute for application Serial No. D-112,382, filed January 31, 1944, now abandoned.

On the drawing:

The back of the wallet (not shown) is substantially plain.

I claim:

The ornamental design for a wallet, as shown and described.

CHARLES MEYERS.
